DOOR HANDLE FOR A REFRIGERATOR CABINET

Harry G. Farmlett, Freeport, N. Y., assignor to General Motors Corporation, Dayton, Ohio, a corporation of Delaware

Application November 29, 1955, Serial No. 39,082

Term of patent 3½ years

(Cl. D67—3)

Fig. 4

Fig. 2

I claim:

The ornamental design for a door handle for a refrigerator cabinet, as shown and described.
